(57) **CLAIM**

The ornamental design for a two-part golf tee, as shown and described.

DESCRIPTION

FIG. 1 is a below perspective view of a first embodiment of a two-part golf tee of the present invention;

FIG. 2 is a bottom view thereof;

FIG. 3 is an exploded perspective view thereof;

FIG. 4 is a front view thereof;

FIG. 5 is a left view thereof;

FIG. 6 is a rear view thereof;

FIG. 7 is a right view thereof;

FIG. 8 is a top perspective view thereof;

FIG. 9 is a top view thereof;

FIG. 10 is an upper exploded perspective view thereof;

FIG. 11 is a bottom view of a second embodiment of the two-part golf tee of the present invention;

FIG. 12 is an exploded perspective view thereof;

FIG. 13 is a front view thereof;

FIG. 14 is a left view thereof;

FIG. 15 is a lower perspective view thereof;

FIG. 16 is a rear view thereof;

FIG. 17 is a right view thereof;

FIG. 18 is a top view thereof;

FIG. 19 is an upper exploded perspective view thereof;

FIG. 20 is an upper perspective view thereof;

FIG. 21 is a bottom view of a third embodiment of the two-part golf tee of the present invention;

FIG. 22 is an exploded perspective view thereof;

FIG. 23 is a front view thereof;

FIG. 24 is a left view thereof;

FIG. 25 is a lower perspective view thereof;

FIG. 26 is a rear view thereof;

FIG. 27 is a right view thereof;

FIG. 28 is a top view thereof;

FIG. 29 is an upper exploded perspective view thereof; and,

FIG. 30 is an upper perspective view thereof.
